DESIGN FOR A TRAY FOR COSMETICS

Morris Walhimer, New Haven, Conn.

Application December 30, 1944, Serial No. 117,163

Term of patent 3½ years

(Cl. D58—4)

To all whom it may concern:

Be it known that I, Morris Walhimer, a citizen of the United States, residing at New Haven, in the county of New Haven and State of Connecticut, have invented a new, original, and ornamental Design for a Tray for Cosmetics, of which the following is a specification, reference being had to the accompanying drawing, forming a part thereof:

In the drawing the figure is a perspective view of a tray for cosmetics, showing my new design.

The opposite side and end of the tray for cosmetics are identical with those shown on the drawing.

I claim:

The ornamental design for a tray for cosmetics, as shown and described.

MORRIS WALHIMER.
